UNITED STATES PATENT OFFICE.

WILLIS E. ALLEN, OF AUBURN, MAINE.

WIRE CLOTHES-PIN.

1,253,767.

Specification of Letters Patent. Patented Jan. 15, 1918.

Application filed March 19, 1917. Serial No. 155,751.

To all whom it may concern:

Be it known that I, WILLIS E. ALLEN, a citizen of the United States, residing at Auburn, in the county of Androscoggin, State 5 of Maine; have invented certain new and useful Improvements in Wire Clothes-Pins; and I do hereby declare the following to be a full, clear, and exact description of the invention, such as will enable others skilled in 10 the art to which it appertains to make and use the same.

This invention relates to improvements in clothes pins and particularly to the type of pivoted jaw pins.

15 One object of the present invention is to provide a device of this character which is simple and cheap in construction, and durable in operation.

Another object is to provide a device of 20 this character with which the clothes as well as the line are arranged to be clamped.

Another object is to provide a device of 25 this character which will be less liable to deterioration than the common wooden clips now used.

Other objects and advantages will be apparent from the following description when taken in connection with the accompanying drawing.

30 In the drawing:

Figure 1 is a side elevation of a clothes pin made in accordance with my invention, and engaging a line and garment.

Fig. 2 is top plan view of the same, partly 35 in section.

Fig. 3 is an elevation view from a position at right angles to that of Fig. 1.

Fig. 4 is a sectional view taken on the line 2-2 of Fig. 3.

40 Referring particularly to the accompanying drawing A and B represent the side members of the clothes pin. Each of said members is formed from a single length of suitable stiff and non-corrosive wire, the 45 same being bent into an elongated loop 10 with the ends extending past each other as shown at 11 and 12. The end 11 is slightly offset, as clearly shown, to permit the other

end 12 to lie in such position as to form a continuation of the remaining portion of the 50 other end.

The unbroken side portion of each of the loops, at points adjacent one end thereof, is formed with two kinks or bends 13 and 14. In the broken side of each loop, the passing 55 ends are each bent into alining kinks 15 and 16, these kinks alining with the kinks of the unbroken sides of the loops. Within the kinks 13 of both loops is disposed a coil spring 17, the ends 18 of which are engaged 60 with the loop members at points between the said kinks. It will be noted that between the kinks there are formed depressions 19, and into these depressions the said ends of the spring are engaged. Thus the said ends 65 are held from disengagement from the loop members.

The other kinks are arranged to embrace the clothes line 20, as seen in Fig. 1, while the portions below said kinks firmly grip 70 the garment therebetween.

The device is extremely simple and cheap in construction, being formed from three pieces of material, the two loop members, each of which is a single length of wire, and 75 the coil spring.

What is claimed is:

A clothes pin formed from wire, and including a pair of elongated loop members each formed from a single length of wire 80 and having the ends disposed in overlapping relation, one end being offset to receive the other end, each of the side portions of each of said loop members being formed with a pair of outwardly extending kink portions 85 resulting in depressions therebetween, and a coil spring seated within the corresponding kinked portions of the loops and having its ends engaged with said loop members in the depressions between said kink portions. 90

In testimony whereof, I affix my signature in the presence of two witnesses.

WILLIS E. ALLEN.
